CLAIM

The ornamental design for a transparent dispenser for rolled film, as shown and described.

DESCRIPTION

FIG. 1 is a front perspective view of a transparent dispenser for rolled film showing my new design;

FIG. 2 is a front elevational view thereof;

FIG. 3 is a right side elevational view thereof, with the lid shown in an open position and the left side being a mirror image of that shown and,

FIG. 4 is a rear elevational view thereof.
